UNITED STATES PATENT OFFICE

2,131,246

CARBURETOR

Claude Wilson, Los Angeles, Calif.

Application October 27, 1936, Serial No. 107,807

1 Claim. (Cl. 261—83)

This invention relates to carburetors, and the general object of the invention is to provide an improved carburetor, which will most effectively break up the gasoline and air into finer particles, and more intimately mix the same than is possible with other carburetors, thus providing for more complete combustion of the gas and greater power and mileage per unit of gas.

My carburetor is particularly applicable to gas engines of the V type, but may be used to advantage on other types of gas engines.

Other objects and advantages will appear hereinafter.

The invention is illustrated in the annexed drawing, which forms a part of this specification and in which

Fig. 1 is a side elevation of my invention, and the generator of a V-type gas engine, said generator being shown connected to my invention for operating the same.

Fig. 2 is a longitudinal vertical section of my invention taken on line 2—2 of Fig. 3.

Fig. 3 is a front end elevation of my invention.

Fig. 4 is a transverse vertical section taken on line 4—4 of Fig. 2.

Fig. 5 is a fragmentary longitudinal section taken on line 5—5 of Fig. 3 illustrating one of the fuel inlet valves.

Fig. 6 is a fragmentary horizontal section taken on line 6—6 of Fig. 2, but showing the rotary gas mixer in elevation.

Referring more particularly to the drawing in which corresponding parts are designated by the same reference characters, my carburetor comprises generally a casing 1, provided with an air inlet 2, and gas outlet 3, a rotary gas mixer 4 in said casing; a hand throttle fuel inlet needle valve 5; and a foot throttle fuel inlet needle valve 6.

The casing 1 includes a cylindrical mixing chamber 7 closed at one end by a head 8 and at the other end by a head 9 in which the air inlet 2 and an air chamber 10 are formed, with said air inlet leading into said air chamber. The gas outlet 3 leads from the lower side of the mixing chamber 7 and is connected to the inlet manifold 11 of a gas engine. The casing head 9 is provided with a port 12 in its lower portion through which air passes from the lower end of the air chamber 10 into the lower portion of the mixing chamber 7. The casing head 9 is also provided with two tubular fuel inlets 13 and 14 located in the upper portion of said head in horizontally-spaced relation and extending a short

distance into the adjacent end of the mixing chamber 7.

In the air inlet 2 is located a butterfly outlet valve 15 on the shaft 16 of which is secured an operating arm 17 to which is connected a conventional operating means not shown.

The construction of the fuel inlet valves 5 and 6 is the same, each comprising a conical valve closing member 18, a stem 19 on the inner end of which said closing member is formed, a seat 20 for said closing member and a needle 21 extending inwardly from said closing member through a seat sleeve 22 into a nozzle 23, in the base 24 of which nozzle said seat sleeve 22 is fitted, and said nozzle base is screw seated at 25 in the inner end of a valve chamber 26 which chamber is fitted in an opening 27 in the outer wall of the air chamber 10, and the inner portion of said valve chamber extends into said air chamber, while the outer portion of said valve chamber extends outside of said air chamber, there being an external flange 28 on said valve chamber 26, which engages the outside of the outer wall of said air chamber and is secured to said wall by screws 29. In the outer end of the valve chamber 26 a packing box 30 is screw seated at 31, through which packing box extends the valve stem 19. The outer portion of the valve chamber 26 is formed with a fuel inlet nipple 32, the outer end portion of which is threaded as at 33 for connection to a fuel line (not shown). The valve nozzle 23 of the fuel-inlet valve 5 extends into the tubular fuel inlet 13, while the nozzle 23 of the fuel-inlet valve 6 extends into the tubular fuel inlet 14. The inner end of the valve chamber 26 of the fuel-inlet valves 5 and 6 extends to a short distance from the outer side of the casing head 9, providing restricted spaces 34 between the inner ends of said valve chambers and said head 9, through which spaces air passes from the air chamber 10 through the tubular fuel inlets 13 and 14 respectively into the adjacent end of the mixing chamber 7.

In the mixing chamber 7 is mounted the rotary gas mixer 4 which comprises a shaft 35 a plurality of perforated blades 36 and a plurality of perforated blades 37. The shaft 35 is journaled at its ends in ball bearings 38 and 39, respectively, in the heads 8 and 9, respectively, of the mixing chamber 7, and one end of said shaft extends outwardly through the head 8. A spider 40 is secured on said shaft intermediate its ends and centrally over the gas outlet 3 in the mixing chamber 7. The blades 36 are secured at their inner ends to the spider 40 and at their outer

ends to a ring 41 surrounding the shaft 35, and are inclined in the direction of rotation of the mixer 4, from said ring to said spider, so that said blades can never be brought into axial alignment with the valve nozzles 23, which would intermittently partly shut off the discharge of fuel from said nozzles into the mixing chamber 7 during rotation of the mixer 4 and impair the efficiency of the carburetor. The blades 37 are secured at their inner ends to the spider 40 and at their outer ends to a ring 42 surrounding the shaft 35 and are inclined in the direction of rotation 9, the mixer 4 from said ring to said spider, and the blades 37 are positioned directly opposite the blades 36 so that the fuel and air entering the mixing chamber 7 from the valve nozzle 23 and through the tubular inlets 13 and 14 and port 12, between any two blades 36, will fill the space between said blades and the two oppositely disposed blades 37, and the mixed fuel and air will be directed during rotation of the mixer 4 by the inclination of the blades 36 and 37, centrally of the lower part of the mixing chamber 7 and out of said chamber through the gas outlet 3.

The outer end of the mixer shaft 35 is connected by a universal joint 43 to the shaft 44 of a generator 45 of a V-type gas engine, or to any suitable driven shaft.

30 The outer ends of the stems 19 of the fuel-inlet valves 5 and 6 are connected respectively by universal joints 46 and 47 to a hand throttle and a foot throttle respectively of a motor vehicle.

The operation of my invention is as follows:

35 The air inlet valve 15 being open to admit sufficient air through the inlet 2 into the air chamber 10 and through port 12 and inlets 13 and 14

into the mixing chamber 7, and the hand throttle valve 5 being opened to admit fuel through the tubular inlet 13, the generator 45 is put in operation by the engine starter, and the rotary gas mixer 4 is rotated by the generator, through the universal joint 43, whereupon the fuel, admitted by the valve 5, and the air, admitted through port 12 and tubular inlets 13 and 14, into the mixing chamber 7, are finely broken up and thoroughly mixed by the perforated blades 36 and 37 of the rotating mixer 4, and the mixed gas is directed by the angularity of said perforated blades out of the mixing chamber through the gas outlet 3 into the engine manifold 11 and the engine (not shown). When the engine is 15 started the valve 5 is closed and the foot throttle valve 6 is opened, whereupon fuel is admitted through said valve and the tubular inlet 14 into the mixing chamber 7, and said fuel is broken up and mixed with the air in said mixing chamber 20 and delivered through the outlet 3 and intake manifold 11 into the engine as aforesaid.

I claim:

In a carburetor, a cylindrical mixing chamber having a fuel and air inlet in one end thereof and a mixture outlet in its cylindrical wall substantially at its central point, a rotary gas mixer mounted in said mixing chamber, said rotary gas mixer comprising a shaft extending axially of said mixing chamber and a plurality of substantially radially-extending perforated flat blades, the blades along the length of said axial shaft being slightly inclined from their opposite ends to the central point of said rotary gas mixer, and the inclination of said blades being in the direction of rotation of said rotary gas mixer.

CLAUDE WILSON.
